(57) **CLAIM**

The ornamental design for a TV monitor stand, as shown and described.

DESCRIPTION

FIG. 1 is a front perspective view of an adjustable TV monitor stand including a platform for supporting a TV monitor; FIG. 2 is a front view thereof; FIG. 3 is a rear view thereof; FIG. 4 is a top view thereof; FIG. 5 is a bottom view thereof; FIG. 6 is a right side view thereof; FIG. 7 is a left side view thereof;

FIG. 8 is a perspective view of the adjustable TV monitor stand showing the stand in a highest position supporting a TV monitor; and,

FIG. 9 is a perspective view of the adjustable TV monitor stand showing the stand in a middle position supporting a TV monitor.

The TV monitor shown in broken lines in FIGS. 8 and 9 shows unclaimed environment and forms no part of the claimed design.

1 Claim, 9 Drawing Sheets
